MARKING GAUGE

Filed July 3, 1928

UNITED STATES PATENT OFFICE

KRISTIAN E. VELLING, OF WINTHROP HARBOR, ILLINOIS

MARKING GAUGE

Application filed July 3, 1928. Serial No. 290,246.

This invention relates to marking gauges and a door casing constructed with an off-set especially serviceable for use in marking the boards of window and door casings, although capable of general use.

The primary object of the present invention is to provide an extremely simple and efficient gauge by means of which a carpenter may quickly and accurately mark the boards of a door or window casing so that the same may be properly cut to insure an accurate and close fit.

A further important object of the present invention is to provide a marking gauge which may be used to advantage in marking the exact line for cutting base boards for fitting them between the corner of a room and the sides of a door casing.

More particularly, the invention contemplates the provision of an improved marking gauge of the above kind having an adjustable abutment or contact member, whereby the exact line for cutting a base board for fitting it between the corner of a room and a door casing may be accurately gauged and marked, even though the lower portion of the adjacent side of the door casing may be constructed with a projecting portion or offset of lesser height than the distance between the fixed end abutments or contacts of the marking bar of the gauge.

A still further object is to provide a marking gauge characterized as above, which is extremely simple in construction, economical to manufacture, and adapted to be readily placed into practical use.

The invention consists in the novel form, combination and arrangement of parts hereinafter more fully described, shown in the accompanying drawing and claimed.

In the drawing:

Figure 1 is a perspective view of a marking gauge embodying the present invention.

Figure 2 is an enlarged transverse section on line 2--2 of Figure 1.

Figure 3 is an enlarged perspective view of the adjustable contact or abutment.

Figure 4 is a fragmentary perspective view illustrating a manner of using the gauge in marking the line for cutting a base board for fitting it between the corner of the room

at the bottom of its adjacent side portion. Figure 5 is a view similar to Figure 4 showing the manner of using the gauge in

marking the line for cutting a base board when the adjacent side of the door casing is not provided with an offset at its lower end; Figure 6 is a fragmentary perspective view illustrating the manner of using the gauge in marking the line for cutting a side member of a window casing.

Referring more in detail to the drawing, the present marking gauge embodies an elongated sheet metal or other suitable bar 5 having a straight longitudinal marking edge 6 and provided with end portions 7 bent at right angles to the main body portion to form contacts or abutments to engage an edge of a board or casing member to which the board to be cut is to be fitted. The edges 8 of the abutments 7 are in the same plane as the straight edge 6 of the bar 5, and said abutments 7 are provided with turned terminal flanges 9 so as to have more effective and firm contact with the casing.

Formed integral with the other longitudinal edge 10 of the marking bar 5 intermediate the ends of the latter is a relatively large wing 11 which extends outwardly at an angle to the bar 5 and forms a convenient handle by means of which the tool may be manipulated.

The gauge, constructed as thus far described, is suitable for several methods of use, examples of which are shown in Figures 5 and 6. In Figure 5 the gauge is illustrated in use for marking the line for cutting a base board 12 for fitting it between the corner of a room and the lower end of the side member

13 of a door-casing or frame having a straight edge 14 continued to the floor of the room. In this use, the end of the base board 12 which is not shown is temporarily engaged with the preceding section of base board at a corner of the room, while the end of the base board 12 which is shown is placed against the lower end of the side casing member 13 as illustrated.

The bar 5 is previously placed across the base board with the fixed end abutments 7 projecting beyond said base board at the

opposite edges of the latter as shown, the bar 5 being of greater length than the width of the board 12 to permit this positioning of the gauge. The gauge is then forced toward the 5 side casing member 13 until the edges 8 of the abutments 7 engage the adjacent straight edge 14 of the casing member 13. A suitable marker, such as a pencil, may then be drawn along the straight edge 6 to mark the exact 10 line for cutting the base board or sawing the end of the same off whereby it will be accurately and closely fitted against the edge 14 of the side frame member 13.

In Figure 6, the gauge is shown in use for 15 marking a side member 15 of a window casing or frame, in which case the member or board 15 is temporarily supported at its bottom upon the bottom member 16 of the window frame, while its upper end is swung 20 against the upper member 17 of said frame. The marking bar 5 is then laid across the upper end of the casing member 15 and pushed upwardly until the abutments 7 engage the bottom edge of the frame member 17. The 25 pencil or other marker is then drawn along the straight edge 6, which is uppermost, so as to mark the exact line where the frame member 15 is to be sawed off to accurately fit it between the frame members 16 and 17.

30 As shown in Figure 4, the side member 13a of a door frame is often constructed at its lower end with a part 18 whose outer edge projects or is offset outwardly of the main straight edge 14a of said side member 13a of 35 the door frame or casing. As this member or part 18 is usually of considerably less height than the length of the marking bar 5, the abutment 7 which is uppermost cannot be engaged with the adjacent edge of the part or member 18 for properly plumbing the gauge 40 so that a line may be properly marked on the base board 12a for accurately fitting the latter against the adjacent outer edge of said member or part 18. In order to adapt the gauge 45 for proper use under these conditions, I provide the same with a longitudinally adjustable abutment or contact. As shown, this adjustable contact consists of an angular strip of metal providing an attaching arm 19 adapted 50 to be flatly disposed against the inner face of the marking bar 5 transversely of the latter and provided with a central opening 20 to receive a clamping bolt 21 which also passes through a central longitudinal elongated slot 55 22 in the marking bar 5 and receives a clamping nut 23 by which the adjustable contact is fixed in any of its adjusted positions. The slot 22 preferably extends substantially from end to end of the marking bar 5 so that the 60 adjustable contact may be employed in conjunction with either end fixed contact or abutment 7 at any required distance from the same. The angular strip from which the adjustable contact is formed also provides a contact arm 65 or abutment member 24 projecting at right

angles to the attaching arm 19 in the same direction as the abutments 7 and attached to the marking bar 5 so that its outer face is in the same plane with the straight edge 6. Any suitable means may be provided for maintaining the adjustable abutment against rotation about the bolt 21 and with the outer face of the contact arm 24 parallel with the plane of the edge 6, such as outwardly projecting lugs 75 25 on the upper and lower edges of the attaching arm 19 adapted to slidably fit in the longitudinal slot 22 of the marking bar 5.

In the use of the invention as shown in Figure 4, the gauge is positioned as shown and described above in connection with Figure 5 except that the lower fixed abutment or contact 7 is engaged with the outer edge of the frame part or member 18 at the bottom of the latter, while the adjustable contact is fixed in a position to have the outer face of the contact arm 24 engage said edge of the part or member 18 near the top of the latter, as illustrated. It is thus apparent that even though the upper fixed contact 7 is located above the top of the frame part 18, the gauge may be 80 properly plumbed for utilizing the straight edge 6 in marking a line on the base board parallel with the outer edge of the frame part 18, whereby an accurate fit will be had when the base board is sawed off along this line 85 marked thereon. Obviously, the adjustable abutment may be readily adjusted upon loosening the nut 23, whereupon the same may be secured in the desired adjusted position by again tightening said nut.

90 The gauge constructed as above described is simple and durable in construction, economical to manufacture, and capable of being readily placed into practical and efficient use.

95 Minor changes may be made without departing from the spirit and scope of the invention as claimed.

100 What I claim as new is:

1. A marking gauge of the character described, comprising a marking bar having a straight longitudinal marking edge and a pair of fixed projecting end abutments, said marking bar being adapted to extend across the board to be marked and to project beyond the opposite edges of said board to permit the end abutments to engage the edge of the board or object to which the first mentioned board is to be fitted, and a further abutment carried by and adjustable longitudinally of said marking bar, said adjustable abutment being adjustable substantially from end to end of said marking bar for selective cooperation with either one of said fixed end abutments, substantially as described.

110 2. A marking gauge for the frames of door casings and the like comprising a sheet metal marking bar having a straight longitudinal marking edge and provided with end portions bent at right angles to the body portion thereof to form end abutments, the marking edge 115 120 125 130

of said bar and the adjacent side edges of said fixed end abutments being in the same plane, and a further abutment carried by and adjustable longitudinally of said marking bar, said adjustable abutment comprising an angular strip of metal having an attaching arm and a contact arm, said marking bar having a longitudinal elongated slot extending substantially from end to end thereof, a clamping bolt extending through the attaching arm of said adjustable abutment and the slot of the marking bar for slidably connecting said adjustable abutment to the latter, the outer face of said contact arm of the adjustable abutment and the marking edge of said marking bar being in the same plane.

3. A marking gauge for the frames of door casings and the like comprising a sheet metal marking bar having a straight longitudinal marking edge and provided with end portions bent at right angles to the body portions thereof to form end abutments, the marking edge of said bar and the adjacent side edges of said fixed end abutments being in the same plane, and a further abutment carried by and adjustable longitudinally of said marking bar, said adjustable abutment comprising an angular strip of metal having an attaching arm and a contact arm, said marking bar having a longitudinal elongated slot extending substantially from end to end thereof, a clamping bolt extending through the attaching arm of said adjustable abutment and the slot of the marking bar for slidably connecting said adjustable abutment to the latter, the outer face of said contact arm of the adjustable abutment and the marking edge of said marking bar being in the same plane, the attaching arm of said adjustable abutment having projecting lugs on the side edges thereof engaging in the longitudinal slot of said marking bar to prevent turning of said adjustable abutment about said clamping bolt.

45 In testimony whereof I affix my signature.
KRISTIAN E. VELLING.
